UNITED STATES PATENT OFFICE.

PASQUALE PASCALE, OF NEW YORK, N. Y., ASSIGNOR TO DRI-STEAM VALVE CORPORATION, A CORPORATION OF DELAWARE.

STEAM VALVE.

Application filed November 12, 1925. Serial No. 68,718.

This invention relates to a steam valve, of the kind especially adapted for use on locomotives, but it is not limited to such use.

It is important under existing conditions governing the building of locomotives that various economies be practiced, and that the capacity and efficiency of the engine be increased without increasing materially the height of the locomotive, the steam dome and the size of the boiler space. These have already been reduced in present locomotive building to such an extent that difficulties are being encountered with the proper life and maintenance of superheater equipment, because too much water is drawn over through the throttle into the superheater which results in decreasing the efficiency of the superheater with a resultant increasing cost of maintenance.

20 The present invention contemplates the provision of a valve in which there is combined, a balanced stop valve and means for drying the steam as it passes through the valve, which latter element comprises a device which may be termed a "steam dryer".

The objects of the invention are several. The primary object is to thoroughly dry the steam as it passes through the valve, and to "superheat" the steam by breaking it up into attenuated streams or divisions, and delivering it to its work free of moisture, and at a temperature substantially that of the temperature in the boiler.

Another object of the invention is to separate the water in the boiler as far as possible or feasible from the point at which the steam passes into the valve, or in other words, break the contact between the steam and water so that the danger of water being carried into the valve with the steam is reduced to a minimum.

A further object of the invention is to provide a valve that will act as a valuable auxiliary to the superheater ordinarily used.

45 In that, when dry steam is delivered to the superheater, it becomes unnecessary to heat the superheater to the degree necessary heretofore, and to increase boiler efficiency by providing a device that will increase the capacity of a locomotive without increasing its size; to increase fuel and water economy, and finally to increase superheater efficiency and prolong its life, since the delivery of dry steam to the superheater, as before intimated, eliminates the possibility of there

being deposited in the superheater substances such as lime and magnesia, with their resultant disadvantages in operation, as well as necessities of frequent attention.

A further object of the invention is to so construct the valve that the point of entrance of the steam into the valve will be at a high point, thus enabling the valve to be supported at a high point above the water in the boiler, thereby lessening the likelihood of drawing over boiler moisture, and steadyng the water in the boiler.

A still further object is to provide a valve in which the water of condensation will not pass through the valve, but be returned to the boiler with no appreciable loss in heat units.

In the drawings illustrating the invention, Figure 1 is a vertical section of the valve, constructed in accordance with my invention.

Figure 2 is a detail section taken about the line A—B of Figure 1, showing a portion of the turbine ring or cage through which the steam passes before entering the valve body.

Figure 3 is a front elevation of the valve.

Figure 4 is a side elevation, showing the position of the valve in a boiler, such as a locomotive boiler.

Referring to the drawings, the numeral 1 designates the stationary body portion of the valve which is provided with ports 2 at proper intervals. It is formed with a central inverted dome portion 3, to make room for the head of the pilot valve which will be later described. The body is formed with an annular flange 4, which is bolted to a similar flange 5 of the outlet pipe 6.

Surrounding the valve body is a cylindrical casing 7, flanged at its bottom, as indicated 8, and secured to the flange 4 by bolts 5. The upper end of the casing is provided with an annular flange 9, which forms a seat for a flange 10 of a "turbine" ring or cage 11, the ring being made up in the main of a series of vanes 12, so spaced apart, and so formed, that they will present angular openings 13, through which steam passes, with a whirling motion, into the steam space or conduit 14, formed between the casing shell and the body of the valve. The top of the cage is closed by a plate 15, secured to the ring in any suitable manner. Within the valve body is a cylinder 16, which is bored throughout the greater part of its

surface, to form small apertures or nozzles 17, contracted at their inner ends and arranged in circumferential rows, as clearly shown in Figure 1. The upper end of this cylinder is formed with a short annular flange 18, which abuts against a rib 19 on the valve body, thus providing opportunity for an annular vertical recess 19', which makes the perforations or apertures in the 10 upper part of the cylinder accessible to the steam as it passes through the ports in the valve body. The lower end of the cylinder is provided with a flange, indicated at 20, which rests upon the flange of the outlet pipe and is received within a recess 21 in the thickened lower part of the valve body, as shown. Thus this flange 20, together with the metal of the valve body, serves as a gasket. Integral with the body of the 15 valve is formed an upstanding flange 22, bevelled at its upper edge, as indicated at 23, to form a valve seat for the correspondingly bevelled end 24 of the slidable stop valve 25. This valve snugly fits against the 20 upper part of the valve body, and against the plate 15 of the cage 11.

The central portion of the valve 25 is enlarged as indicated at 26, and the enlargement is bored as indicated at 27, to form a 25 recess for the passage of steam under proper conditions as will now appear. This enlargement is further bored and threaded for receiving a threaded sleeve 28, in which works the stem of the pilot valve. The 30 lower part of the stem carries a head 30, designed to limit the upward movement of the pilot valve as a whole, and the stem above the head is provided with a plurality of splines 31, which serve to space the stem 35 away from the inner periphery of the sleeve, and thus form steam passages through which steam may pass to the space between the dome of the valve body and the top of the stop valve, to balance the valve. The upper 40 part of the sleeve is provided with a bevelled seat 32, and the upper part of the pilot valve stem is enlarged and bevelled as indicated at 33, thus forming a valve that cooperates 45 with the seat 32 to open and close communication as the exigencies may require.

The upper end of this pilot valve is bifurcated as indicated at 34, for the reception of a cross bar 35, which is held centrally in the bifurcation by a pin 36. To the outer 50 ends of this bar are connected the upper ends of the operating levers 37. Formed upon the outlet pipe and oppositely disposed are two hanger ears 38. These form bearings for a rod 39, to each end of which is 55 fixedly mounted a bell-crank lever 40, and to the arms 41 of these levers are pivoted the lower ends of the operating levers 37. Tight 60 on the rod 39 is a sleeve provided centrally with a link 43, to whose lower end is pivoted 65 the valve operating rod 44.

Integral with the flange of the outlet pipe is an inclined plate 45, whose lower edge, when the parts are assembled, rests against a lug 46, integral with the pipe. Secured to this plate is a bracket 47, whose upper end 70 is firmly secured to a transverse support 48 in the steam dome, and it is by this means that the valve as a whole is supported.

Reverting to the valve body, it will be noted that the flange 22, which constitutes 75 the seat for the stop valve, is spaced considerably from the wall of the perforated cylinder. This is for the purpose of permitting steam to have access after passing through the ports to reach the lowermost nozzles or 80 perforations in the cylinder.

At intervals this flange is provided with drain holes 49, and similar holes are provided in the casing 7, as indicated at 50. Thus it will be seen that any accumulation 85 of moisture or water from the steam will be led back into the boiler with no appreciable diminution in heat units.

Claims:

1. In a steam valve, in combination, a 90 ported hollow body closed at its top and provided with an annular valve seat, a casing surrounding said body and spaced therefrom, a stop valve enveloping a portion of said body and slidable over the ports 95 therein and adapted to seat on said seat, the casing together with the stop valve forming a steam conduit communicating with said ports when said stop valve is open, a cage at the entrance of the conduit including means 100 for dividing the steam into attenuated streams and directing the resultant currents into said conduit, a cylinder in the valve body and provided with numerous small holes constituting nozzles communicating 105 with said ports where-through the steam is wire-drawn and dried in passing into said cylinder.

2. In a steam valve, in combination, a hollow body having ports therein, and a valve 110 seat below said ports, a stop valve enveloping a portion of said body and slidable relative thereto, over said ports, and adapted to seat upon the valve seat, a casing surrounding said valve and spaced therefrom, said 115 casing, together with the body of the stop valve, forming a conduit communicating with said ports when said stop valve is open, a cage located at the top of said conduit, said cage being closed at its top and formed of numerous vanes through which the incoming steam is directed into said conduit, a cylinder in the hollow body and provided 120 with numerous small holes constituting nozzles through which the steam is wire-drawn and dried, said nozzles communicating with said ports.

3. In a steam valve, in combination, a ported hollow body closed at one end and provided with an annular valve seat, a stop 125

- valve enveloping a portion of said body and slidable over the ports therein, a casing surrounding said body and spaced therefrom and forming the outer wall of a steam conduit communicating with the ports of said hollow body when said stop valve is open, a cage located at the entrance of the conduit, said cage being closed at its top and comprising numerous vanes so positioned as to 10 form steam passages upon axes different from the axis of the hollow body, through which the incoming steam passes and is directed into the conduit, a cylinder in the body and provided with numerous small 15 holes constituting nozzles, communicating with the ports, said holes being arranged circumferentially of the said cylinder and means for balancing the steam pressure on both sides of the stop valve.
- 20 4. In a steam valve, in combination, a hollow body having ports therein, said body being closed at its top and provided with an annular valve seat, a stop valve surrounding said body slidable over said ports, and 25 adapted to seat upon the valve seat, a casing surrounding the body and spaced therefrom and forming with the body of the stop valve, a conduit communicating with said ports when said stop valve is open, a cage surrounding the body at the entrance of said conduit, closed at its top and open at its bottom, said cage including numerous vanes spaced apart to form steam passages through which steam is directed into said conduit, a 30 cylinder in the body and provided with numerous small holes constituting nozzles communicating with the ports, said holes being arranged circumferentially in the cylinder, said cylinder at its lower end being spaced 35 from the valve seat to form an annular drainway, there being provided at the bottom of the drainway means for permitting the water of condensation to drain back into the boiler.
- 40 5. In a steam valve, in combination, a hollow ported body closed at its top, and provided with an annular valve seat, a casing surrounding said body and spaced therefrom, a stop valve enveloping a portion of 45 said body and slidable over the ports therein, and adapted to seat on said seat, the casing together with the stop valve, forming a 50 steam conduit communicating with the ports in said hollow body when the stop valve is open, and a cylinder in the body and provided with numerous small holes constituting nozzles where-through the steam is wire-drawn and dried while passing into said cylinder, said nozzles communicating with said ports. 55
- 60 6. In a steam valve, in combination, a hollow body having steam inlet ports therein and provided with an annular valve seat, a cylinder in the hollow body and provided with numerous small holes constituting nozzles, wherethrough the steam is dried in passing into said cylinder, said nozzles communicating with said ports, said cylinder being spaced from the seat to form a drainway around said cylinder, means for 65 conducting the water of condensation from the said drainway back into the boiler, and a stop valve enveloping a portion of said body and adapted in its movement to control the ports in the valve body and to seat upon the valve seat. 70
- 75 7. In a steam valve, in combination, a hollow body having steam inlet ports therein, and provided with an annular valve seat, a cylinder in the hollow body and having steam passages through its walls, communicating with said ports, said cylinder being spaced from the valve seat to form a drainway around said cylinder and means for conducting the water of condensation from said drainway back into the boiler, and a stop valve slidable on said body over said ports, and adapted to seat on said seat. 80
- 85 8. In a steam valve, in combination, a hollow ported body closed at one end and provided with an annular valve seat, a casing surrounding said body and spaced therefrom, a stop valve enveloping a portion of said body and adapted to seat on said seat, the casing arranged to cooperate with said hollow body to form a steam conduit communicating with the ports in said body when said stop valve is open, means within the hollow body for wire-drawing and drying the steam after it passes through said body. 90
- 95 In testimony whereof he affixes his signature.

PASQUALE PASCALE.
